Wes. 1340

Thomas A. Carew, of Cambridge, Mass.
Letters Patent No. 1340. Dated Nov. 13th, 1860.

The schedule referred to in these Letters Patent and making part of the same.

To all whom it may concern:

Be it known that I, Thomas A. Carew, of Cambridge, in the County of Middlesex and State of Massachusetts, have invented a new design of a Medallion; of which the following is a full, clear and exact description, reference being had to the accompanying drawing, making part of this specification in which, is represented a likeness in relief of the late Reverend Theodore Parker, and I wish to identify the same by the following distinguishing features.

The top *a*, of the head is bald, the hair *b*, being worn only on the back part of the head, and immediately over the ear *c*. The beard *d*, covers the chin up to the point *e*, and the side of the face up to the ear, forming with the hair at *f*. The bust *g*, is cut off by a curved line *h*.

Claim

What I claim as my invention and desire to secure by letters patent, is the above described likeness in relief of the Reverend Theodore Parker.

Witnesses:

Chauncy Smith,
Wm. L. Whitney.

Thos. A. Carew
